UNITED STATES PATENT OFFICE

LEROY WILCOX, OF DETROIT, MICHIGAN, ASSIGNOR, BY MESNE ASSIGNMENTS, TO COPE-SWIFT CORPORATION, A CORPORATION OF MICHIGAN

OIL BURNER

Application filed August 1, 1928. Serial No. 296,766.

This invention relates to oil burners such as are used in connection with furnaces and the like for heating residences or other buildings, or for other purposes, and is in part disclosed in my application for Letters Patent of the United States for improvements in oil burners, filed November 18, 1927, and granted on November 26, 1929, as Patent No. 1,736,990, the principal object being the provision of an improved construction for atomizing liquid fuel.

Another object is to provide means for atomizing the fuel in an oil burner comprising a pair of rotating cups, one of which is positioned within the other, oil being fed into the inner cup from which it is discharged in a finely divided state into the outer cup from which it is finally discharged into the air stream.

Another object is to provide, in combination with the atomizing cup of an oil burner, an auxiliary atomizing means comprising a rotatable member adapted to discharge oil therefrom into the interior of the atomizing cup.

A further object is to provide atomizing means for an oil burner comprising a cup-shaped member having therein an auxiliary atomizing member spaced from the walls thereof, such auxiliary member being provided with means at its discharge end whereby oil fed to the interior thereof will be broken up by said means in being discharged from said auxiliary member into the cup member.

The above being among the objects of the present invention, the same consists in certain features of construction and combinations of parts to be hereinafter described with reference to the accompanying drawings, and then claimed, having the above and other objects in view.

In the accompanying drawings which illustrate suitable embodiments of the present invention, and in which like numerals refer to like parts throughout the several views,—

Fig. 1 is a vertical sectional view taken through the longitudinal center of an oil

burning apparatus constructed in accordance with the present invention.

Fig. 2 is an enlarged fragmentary sectional view showing the inner vaporizing cup or member.

Fig. 3 is an enlarged fragmentary sectional view showing a modification of the inner vaporizing cup or member.

Fig. 4 is a sectional view taken on the line 4—4 of Fig. 3.

Figs. 5 and 6 are enlarged fragmentary sectional views of other modifications of the inner vaporizing cup or member.

As indicated in the drawings, a supporting plate member 16 is provided which is adapted to close an opening in a furnace and may be secured thereto by screws or other suitable means, not shown. The plate 16 is open at its center and extending inwardly.

70 Therefrom with its walls in inwardly converging relationship is a casing 18 which may be integrally formed with the plate 16. A circular casing 19 is secured to the inner end of the casing 18 by bolts such as 20 and nuts

21 which pass through flanges 22 and 23 formed on the casings 18 and 19 respectively, and extends inwardly therefrom with its walls in outwardly diverging relationship.

75 Closing the rear face of the open center of the plate 16 is a plate 24 provided with a relatively large central opening 25, it being held in place by being clamped between the flange 26 of the motor supporting frame 27 and the plate 16.

The motor supporting frame 27 which extends outwardly from the plate 24 is located on the plate 16 by means of the dowels 28 and is secured thereto by means of screws 29. The supporting frame 27 is provided with a plurality of openings 30 around its circumference for the entrance of air to the interior of the same.

80 Removably secured within the rear end of the frame 27 by means of set screws 31 is an electric motor comprising a casing 32, armature 33, armature shaft 34 and bearings 35 and 36, the casing 32 extending into the frame 27 to a point rearwardly of the openings 30 so as not to restrict the flow of air through

85 the latter. To the inner end of the armature shaft 35 is secured an extension 37 by

90 95 100

means of a screw 38, the extension 37 terminating in a flange 39 between which and the sleeve 40 a fan 41 is clamped. A cup-shaped member 42 is secured to the inner end 5 of the sleeve 40 by means of screws 43 which project through the bottom of the cup 42, the flanges of the sleeve 40, the fan 41, and are threadably received in the flange 39 of the extension 37 thus serving to secure all of 10 these parts in assembled relationship. The armature shaft and extension are hollow and extending through the same from the outer end of the motor, and rotatable relative thereto, is an oil delivery tube 44 which terminates 15 at its inner end adjacent the bottom of the cup 42. A second cup member 45 having an opening in its otherwise closed end for the passage of the tube 44 is secured within the sleeve 40 and extends from the inner end 20 of the extension 37 to a point inwardly spaced from the bottom of the cup 42. Suitable packing 47 is secured in the cup 45 around the tube 44 by means of a nut 48 in order to prevent leakage of oil from the interior 25 of the cup 45 back around the outside of the tube 44 to the motor. In Figs. 1 and 2 the inner edge of the cup 45 is provided with a plurality of radial notches or slots 40.

The outer end of the tube 44 which projects out past the rear end of the motor casing 32 is provided with a connection 53 which serves to connect it to a shut-off valve 54. The shut-off valve 54 is connected by a line of piping 55 to a source of oil supply; 35 valves and other mechanism shown in the parent application above referred to, being inserted in the line 55.

In operation, when the armature 33 is rotated it causes rotation of the shaft 35, extension 37, fan 41, sleeve 40 and cups 45 and 42. Rotation of the fan 41 causes air to be drawn through the openings 30 and forces it out between the cup 42 and casing 19. At the same time oil from the pipe 55 is conducted 45 by the tube 44 to the inner cup 45 and in which it is deposited. The rotation of the cup 45 causes the oil therein to travel toward its open end until it reaches the notches 50, the oil thereupon being thrown by centrifugal 50 force through the notches in the form of a fine spray against the inner surface of the cup 42. The oil being fed into the cup 42 is caused by its rotation and the centrifugal force acting upon it to form in a thin film 55 over the interior of the cup 42 and be gradually carried to the open end thereof from which it is thrown off into the air stream between the cup 42 and casing 19 in the form of a finely divided mixture. Part of the 60 oil thrown out of the cup 45 is vaporized by the heat to which the inner end of the apparatus is subjected, and part is vaporized by coming in contact with the air in the finely divided state in which it is thrown 65 out of the cup 45, and this vaporization aids

in cooling the cup 42 and thus prevents carbonizing of the oil before it is thrown off of the cup 42.

The inner cup elements, shown as distinct from the flanged sleeve element 40 but as having an outside diameter which corresponds to the diameter of an opening in the bottom of the outer cup element 42 and adapts it to interfit with the sleeve element 40 and/or the fan element 41 and to abut the hollow shaft element 37, although projecting but slightly inward beyond said bottom opening, may be formed in a variety of different ways so that the oil being discharged therefrom into the outer cup 42 will be broken up in the manner described. In Figs. 3 and 4 one modification of the same is shown. In this case the inner cup 45 has its inner surface serrated as at 56 and the inner end face is backwardly beveled as at 57, the point where the face 57 inter-connects the serrations 56 presenting a plurality of tooth-like projections 58 which act to break up the oil being discharged therefrom to the outer cup element in a manner similar to that which is effected by the use of the grooves 50 in Figs. 1 and 2.

In Figs. 3 and 4 the inner end of the inner cup 45 is provided with a peripheral rib 59 which acts to prevent any oil from travelling back along the outside of the cup 45 and thereby come in contact with the bottom of the cup 42.

In Fig. 5 another modification of the inner cup 45 is shown. In this case the outer surface of the inner end of the cup 45 is threaded and a cap member 60 is screwed onto the same, the cover 60 being provided with a plurality of radially extending openings 61 which serve the same purpose as the slots 50 and teeth 58 in the preceding figures.

The construction shown in Fig. 5 may be modified as shown in Fig. 6 in which the inner surface of the inner end of the cup 45 is internally threaded and is provided with a plug 62, a plurality of radially extending openings 63 being provided in the cup 45 adjacent the plug 62 to effect the same result as the openings 61 shown in Fig. 5. Furthermore, in Fig. 6 the inner wall 64 of the cup 45 is shown as diverging outwardly toward the discharge end of the same in order to facilitate the travel of the oil toward the discharge end thereof during rotation of the same.

Each of the foregoing constructions will 120 be seen to include, regardless to the specific configuration of the inner cup element, special means for holding the same in concentric and leak-obviating relationship to a flanged spool element and/or to an outer cup element having a substantially flat bottom through which extends only an edge of said inner cup element, adapted substantially to close the central opening therein.

It will be obvious that there are other ways 120

of modifying the construction of the inner cup shown to achieve substantially the same result as herein described.

Formal changes may be made in the specific embodiment of the invention described without departing from the spirit or substance of the broad invention, the scope of which is commensurate with the appended claims.

10 What I claim is:

1. In an oil burner, in combination, a rotatable closed bottom cup disposed with its axis in a substantially horizontal plane, a

15 second cup within the first mentioned cup and rotatable therewith, said second cup being provided with a plurality of oil discharge points, a peripherally extending flange on said second cup between said points and the bottom of the first mentioned cup, and means for feeding oil into said second cup.

20 2. In an oil burner, in combination, a pair of rotatable closed bottom cups one disposed within the other, the inner of said cups being formed to discharge a plurality of circumferentially spaced streams of oil therefrom into the outer of said cups, an outwardly radially extending flange on the inner of said cups between said points of discharge thereon and the bottom of the outer of said cups, and means for feeding oil into the inner of said cups.

25 3. In an oil burner, in combination, a rotatable cup adapted to receive a flow of oil, the interior of said cup being serrated axially of said cup, and the open edge surface of said cup being beveled towards the axis of said cup and away from the bottom thereof.

40 4. In an oil burner, in combination, a rotatable cup adapted to receive a flow of oil, certain walls of said cup being serrated axially of said cup, and the open end edge surface of said cup being beveled whereby to form a plurality of axially extending notches in the free edge of said cup where said end surface intersects said serrations, for discharging the oil from said cup in a plurality of separate streams.

45 5. In an oil burner, in combination, a rotatable cup adapted to receive a flow of oil, the interior walls of said cup being serrated axially of said cup, and a radially outwardly extending flange at the open end of said cup, that surface of said flange and cup most remote from the bottom of said cup being beveled towards the axis of said cup and away from the bottom of said cup whereby a plurality of notches are formed at the free edge of said cup where said most remote surface intersects said serrations.

60 6. In a burner organization comprising a fan element, an outer cup element, and an inner cup element all rotatable by a hollow shaft element through which extends an oil

feed tube, means for uniting said elements in coaxial and leak-obviating relationship which comprises: a flanged sleeve provided with means for the support of both of said cup elements.

70 7. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said inner cup element being so received within said sleeve element 75 as to project but slightly within said outer cup element.

75 8. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element including a substantially flat bottom portion 80 having a central opening through which said inner cup element extends.

85 9. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element including a substantially flat bottom portion 90 having a central opening through which said inner cup element extends.

95 10. In a burner organization comprising a fan element, an outer cup element, and an inner cup element all rotatable by a hollow

100 shaft element through which extends an oil feed tube, means for uniting said elements in coaxial and leak-obviating relationship which comprises: a flanged sleeve provided with means for the support of both of said cup elements,—said outer cup element including a substantially flat bottom portion through which extend bolts which are received by said sleeve element.

105 11. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element including a substantially flat bottom portion through which extend bolts which are received by said sleeve element, said bolts extending also into engagement with said fan element.

110 12. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element including a substantially flat bottom portion 115

120 13. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element including a substantially flat bottom portion 125

130 14. In a burner organization comprising a fan element, an outer cup element, and an inner cup element all rotatable by a hollow shaft element through which extends an oil

- through which extend bolts which are received by said sleeve element, said bolts extending also into engagement with said shaft element.
- 5 12. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element including a substantially flat bottom portion
- 10 15 through which extend bolts which are received by said sleeve element, flanges on said sleeve being respectively engageable with said outer cup element and with another of the mentioned elements.
- 20 13. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element being provided with a central opening in the bottom thereof and said inner cup element being of substantially the same diameter as said opening.
- 30 14. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said inner cup element having an outside diameter which corresponds to the inside diameter of said sleeve.
- 40 15. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element being provided with a central opening in the bottom thereof and said inner cup being of such size and shape as to project slightly inward through said bottom opening when secured within said sleeve element.
- 50 16. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said
- 55 cup elements,—said inner cup element being adapted to interfit within two of the mentioned elements.
17. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said inner cup element being interiorly provided with threaded means for the retention of packing therein.
- 60 18. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said inner cup being interiorly grooved and the open end of said cup being provided with a backwardly beveled face whereby tooth-like projections are formed at an inner edge thereof.
- 65 19. In a burner organization comprising a fan element, an outer cup element, and an inner cup element all rotatable by a hollow shaft element through which extends an oil feed tube, means for uniting said elements in coaxial and leak-obviating relationship which comprises: a flanged sleeve provided with means for the support of both of said cup elements,—said outer cup element including a substantially flat bottom portion having a central opening through which said inner cup element extends, said inner cup having a beveled face which inwardly terminates in teeth and a peripheral rib being provided at the outer edge of said beveled face.
